[57] **CLAIM**

The ornamental design for a holder for a utensil lid handle, as shown and described.

DESCRIPTION

FIG. 1 is a perspective view of a holder for a utensil lid handle showing our new design, wherein the holder is shown attached to the handle of a lid illustrated in broken lines;

FIG. 2 is a top view thereof;

FIG. 3 is a side view thereof, the opposite side being identical in appearance;

FIG. 4 is an end view thereof, the opposite end being identical in appearance; and

FIG. 5 is a bottom view thereof.
